CLAIM

The ornamental design for a spray nozzle, as shown and described.

DESCRIPTION

FIG. 1 is a perspective view of a spray nozzle in accordance with the present invention;

FIG. 2 is a top view of the spray nozzle of FIG. 1;

FIG. 3 is a left side view of the spray nozzle of FIG. 1, the right side view being a mirror image thereof;

FIG. 4 is a front view of the spray nozzle of FIG. 1;

FIG. 5 is a back view of the spray nozzle of FIG. 1; and,

FIG. 6 is a bottom view of the spray nozzle of FIG. 1.

In all Figures, the shaded area(s) represent(s) the bounds of the claimed design. All broken lines represent the remaining portion of the spray nozzle, a sprayer shroud, and portions of a sprayer apparatus which are provided for illustrative purposes only and form no part of the claimed design.
